SPOON OR SIMILAR ARTICLE OF FLATWARE

Ford J. Lanzoni, Yalesville, Conn., assignor to International Silver Company, Meriden, Conn.

Filed Nov. 15, 1972, Ser. No. 306,571

Term of patent 14 years

Int. Cl. D7—03

U.S. Cl. D7—137

FIG. 1

FIG. 2

FIG. 3

FIG. 4

FIG. 5

FIG. 7

FIG. 1 is a front elevational view of a spoon showing my new design;

FIG. 2 is a rear elevational view thereof;

FIG. 3 is a side elevational view thereof; and

FIGS. 4 through 7 are enlarged sectional views taken on lines 4—4 through 7—7 respectively, of FIG. 1.

The design is intended for use on sets comprising spoons, forks, knives and similar articles of flatware.

I claim:

The ornamental design for a spoon or similar article of flatware, substantially as shown and described.
